UNITED STATES PATENT OFFICE.

JOHN HARDING COLE, OF INNISHANNON, IRELAND.

GAME APPARATUS.

No. 841,936.

Specification of Letters Patent.

Patented Jan. 22, 1907.

Application filed January 15, 1906. Serial No. 296,118.

To all whom it may concern:

Be it known that I, JOHN HARDING COLE, a subject of the King of Great Britain, residing at Woodview, Innishannon, in the county of Cork, Ireland, have invented certain new and useful Improvements in Game Apparatus, of which the following is a specification, such as will enable those skilled in the art to which it appertains to make and use the same.

This invention relates to games and game apparatus; and the object thereof is to provide an improved apparatus of this class by means of which a novel and interesting game which involves both the features of billiards and croquet may be conveniently played either in a dining-room on an ordinary dining-table or on any similar table or, if desired, upon an ordinary billiard-table; and with this and other objects in view the invention consists in a game apparatus of the class specified constructed as hereinafter described and claimed.

The invention is fully disclosed in the following specification, of which the accompanying drawings form a part, in which the separate parts of my improvement are designated by suitable reference characters in each of the views, and in which—

Figure 1 is a plan view of an ordinary table, such as a dining-table, provided with my improved game apparatus; Fig. 2, a transverse section on the line 2 2 of Fig. 1; Fig. 3, a side view, partially in section, of a marking-column which I employ; Fig. 4, a view similar to Fig. 3, showing another marking-column also employed in my improved game apparatus; and Fig. 5, a side view, partially in section, of a wicket, six of which are employed.

In the drawings forming part of this specification I have shown at *a* an ordinary table, which may be either an ordinary dining-table or a similar table of any kind or class, and this table is preferably covered with cloth, as shown at *b*; but the cloth is not an absolutely necessary feature of the invention. I also provide side and end cushion-rails *c* and *c*², which correspond in length with the length and width of the table, and the said cushion-rails are placed on the side and end edge portions of the table and are held thereon by clamps *d*. The cushion-rails *c* and *c*² are provided at intervals with concave recesses *c*³, and the clamps *d* are yoke-shaped in form and are adapted to be manipulated so that

the ends thereof will engage the cushion-rails at the central portion of the concave recesses *c*³, and then by moving said clamps longitudinally of said rails the latter may be securely locked to the table, as will be readily understood.

My invention, however, is not limited to any particular form of the clamps *d*, and any suitable devices of this class may be employed for securing the cushion-rails *c* and *c*² to the table.

The cushion-rails *c* and *c*² are also provided centrally of their inner sides with cushion-strips *e*, which are countersunk in said rails and which are composed of rubber, rubber and canvas, or any suitable elastic material. I also provide a plurality of wickets *f*, six of which are shown in Fig. 1 and one of which is shown in Fig. 5, and these wickets are weighted and provided with feet *f*², to the bottom of which are secured pads or cushions *f*³, which correspond with the cloth *b*, employed as a covering for the table and which aid in holding the wickets in proper position; but the said cushions or pads *f*³ are not absolutely essential. The wickets *f* may be cast out of any suitable metal, so as to give them the proper weight, or they may be made of any suitable material and be weighted, as will be readily understood, and the separate legs of the wickets are provided at a predetermined distance from the bottom of said legs with annular cushions *f*⁴, composed of rubber or any suitable material, and the wicket itself may also be provided with a flag or flags *f*⁵, which may be used for marking the progress of the game.

I also provide two heavy or weighted columns or towers *g* and *h*, which correspond with the pegs or posts used in the game of croquet, and the column or tower *h* is preferably built to represent a lighthouse and is designed to mark the starting end of the table in playing the game, and said column or tower is also provided with colored bands *g*², and in practice the balls with which the game is played are colored to correspond with said bands, and said bands indicate the order in which the various players begin the game. The other column or tower *h* is preferably made to represent an ordinary Celtic tower and is placed at the end of the table opposite the column or tower *g*, and forms, as does the column or tower *g*, a part of the game apparatus, as clearly indicated in Fig. 1, and the columns or towers *g* and *h* are both provided,

respectively, at a predetermined distance from the base thereof with annular cushion devices g^3 and h^2 , and said columns or towers are also respectively provided with cushions 5 or pads g^4 and h^3 , which are secured to the base thereof.

It will be understood, of course, that the cushion formed by the strip e around the cushion rails or strips c correspond with the 10 cushion devices f^4 , g^3 , and h^2 on the wickets f and towers g and h , and in the playing of the game, which is done by means of balls and mallets, the balls being indicated at i in Figs. 3 and 5, the said balls strike these cushions 15 and rebound freely, and the said cushions, as will be understood, add a very attractive feature to the game apparatus and render the game more attractive and interesting.

In practice the wickets and columns or 20 towers g and h are placed on the table, as indicated in Fig. 1, and the number playing the game is preferably limited to four, although, as will be understood, a different number of players may engage in the game, if 25 desired. The party beginning the game places his ball at j in Fig. 1, and the object to be achieved is to pass the ball over the lines indicated by the arrows x and y , in which operation all the wickets are passed through, 30 and the column or tower h is struck, and from the column or tower h all the wickets are again passed through and the column or tower g is struck. The method of playing the game otherwise than above set out is the 35 same as in croquet, the first player continuing as long as he can count by passing through a wicket and striking a column or tower. The second, third, and fourth players follow the first, the same as in croquet, and the second, third, and fourth player may use the 40 ball of any player preceding him in the same as in the last-named game.

My invention is not, as will be understood, limited to any particular order of playing the 45 game, and any desired rules or regulations may be adapted for this purpose.

Instead of providing the cushion rails or strips e and c^2 , as shown in the accompanying drawings and as hereinbefore described, an 50 ordinary billiard-table may be employed, and the other parts of the apparatus, including the wickets f , the towers g and h , and the balls and mallets, may be used on and in connection with said table, as hereinbefore described.

The mallets used in playing this game are similar to those employed in playing other

games of this class and form no part of this invention and are therefore not shown and described, and this is also true of the balls 60 employed; but for the purpose of indicating the operation of said balls in connection with the cushions on the wickets and towers or columns I have indicated said balls in Figs. 3 and 5.

It will be observed that the cushions f^4 , g^3 , and h^2 , applied to the wickets f and towers or columns g and h , are of such width that the balls used in playing the game will strike said cushions before they strike the base of 70 the said wickets, columns, or towers, and said columns or towers and said wickets should in practice be made of such weight that the balls will not affect or dislodge them.

From the foregoing description it will be 75 seen that my improved game apparatus comprises a table having cushioned rails, members having weighted bases adapted to be placed on said table and provided above the bottom weighted bases with annular cushions 80 which project equal to or beyond said bases, and balls adapted to be placed on said table and to be moved by a mallet or cue, the cushioned rails of the table and the annular cushions on the said upright members serving 85 for the purpose of cushioning the ball or balls or caroming the same when said balls come in contact with said cushions.

Having fully described my invention, what I claim as new, and desire to secure by Let- 90 ters Patent, is—

1. In a game apparatus of the class described, a plurality of movable devices having weighted bases adapted to rest loosely on a table or other support, said devices being 95 provided above their weighted bases and independent thereof with annular cushions which project beyond said bases.

2. In a game apparatus of the class described, a wicket the sides of which are provided with weighted bases adapted to rest on a table or other support, the sides of said wicket being also provided above the weighted bases with annular cushions which project beyond said bases.

In testimony that I claim the foregoing as my invention I have signed my name, in presence of the subscribing witnesses, this 2d day of November, 1905.

JOHN HARDING COLE.
